United States Patent Office

Des. 221,140
Patented July 13, 1971

221,140

BUILDING

Mark A. Wood, 1913 E. 116th St.,
Carmel, Ind. 46032

Filed Nov. 12, 1969, Ser. No. 20,041

Term of patent 14 years

Int. Cl. D25—04

U.S. Cl. D13—1

FIG. 1.

FIG. 4.

FIG. 2.

FIG. 3.

FIG. 5.

FIG. 1 is a front perspective view of a building showing my new design;

FIG. 2 is a right side elevational view thereof with the platform as shown at the left in FIG. 1 in folded position;

FIG. 3 is a front elevational view thereof;

FIG. 4 is a left side elevational view thereof with the platform as shown at the left in FIG. 1 in folded position;

FIG. 5 is a rear elevational view thereof.

I claim:

The ornamental design for a building, substantially as shown.
